JAMES DOUGHERTY, OF PHILADELPHIA, PENNSYLVANIA.

Letters Patent No. 64,645, dated May 14, 1867.

IMPROVEMENT IN CUPOLA FURNACES.

The Schedule referred to in these Letters Patent and making part of the same.

TO ALL WHOM IT MAY CONCERN:

Be it known that I, JAMES DOUGHERTY, of Philadelphia, Pennsylvania, have invented certain improvements in Furnaces or Cupolas, and I do hereby declare the following to be a full, clear, and exact description of the same.

My invention consists, first, of a cupola or blast furnace, the interior of the lower portion of which is composed of a chamber with vertical walls, and above the latter a basin-like chamber contracted at the top, all substantially as described hereafter, this form of furnace being considered best adapted for the rapid melting of metals and reduction of ores; second, of a system of tuyeres having openings so arranged as to discharge a blast of greater volume below than above; third, of certain air openings arranged in respect to an annular projection in the furnace, as described hereafter, so that jets of air may be directed on to the rising products of combustion.

In order to enable others skilled in the art to make and use my invention, I will now proceed to describe its construction and operation, reference being had to the accompanying drawing, which forms a part of this specification, and in which—

Figure 1 is a vertical section of my improved furnace or cupola; and

Figure 2, a sectional plan on the line 1 2, fig. 1.

Similar letters refer to similar parts throughout the several views.

A represents the outer sheet-iron casing of the cupola, B the fire-brick lining, and D the plate on which the cupola is built, and which is supported on columns (not shown in the drawing) in the usual manner. From the base D to the line *x* the interior of the furnace is contracted, so as to form the cylindrical chamber G, and from this line *x* upwards the interior is gradually enlarged, to be gradually reduced as it approaches the line *y*, where there is a prominent annular projection, *m*, from the walls, so that between the lines *x* and *y* is formed a basin, F, of the shape, or approximating to the shape, represented in the drawing. From the line *y* to the line *t* the interior of the cupola is abruptly enlarged, and above the latter line assumes the cylindrical form represented until it approaches the usual chimney or stack with which the cupola is surmounted. Between the lining B of the cupola and the outer casing of the same, and adjacent to the cylindrical chamber G, is formed the annular chamber E, which receives the blast and distributes the same to the several tuyeres. In the present instance there are eight tuyeres, four designated by the letter H, and four by the letter I. These tuyeres consist of cast-iron blocks arranged at equal distances apart, and built in the fire-brick lining. The blocks H are arranged between and are situated somewhat lower than the blocks I, and the holes in the latter differ very materially in shape from those of the former, the holes *h* in the blocks H being round and inclined downwards from the blast-distributing chamber, as shown in the drawing, while the holes *i* in the blocks I are elongated vertically, and are wider below than above. It will be evident that the blast admitted to the cylindrical chamber G will extend in altitude from the point *q* to the point *p*, but that the blast will be of much greater volume below than above, where it has to pass through the contracted upper ends of the elongated openings *i* of the blocks I, whereas it has an exit below both through the larger round holes *h* of the tuyeres or blocks H, as well as through the enlarged lower ends of the said elongated openings. This mode of distributing the blast into the chamber G of the cupola has been found most efficient in practice. The blast-distributing chamber E communicates through an annular passage, *f*, with a small distributing chamber, J, which is situated at the same height as, and adjacent to, the projection *m* of the brick lining, and the chamber J communicates with the basin-like chamber F of the cupola through a number of small inclined passages, *w*, (there are sixteen in the present instance,) terminating a short distance below the said projection *m* of the lining B, hence a number of small jets of air must be projected on to the fuel, effecting a thorough consumption of the unconsumed products of combustion, and rendering material aid in reducing ores or metals. The cupola is furnished with the usual tapping hole, shown by dotted lines at *k*, and with a blast pipe, *l*, through which air is forced into the distributor E. Although I have illustrated and described the interior of the furnace as being circular, it is not essential in the carrying out of my invention that this form should be preserved, as the interior may be of an oblong or oval form, the tuyeres and blast-distributing chambers being arranged accordingly, nor is it imperative that there should be a communication, *f*, between the two blast-distributing chambers E and J, as the latter may

receive the compressed air from independent pipes. The tuyere openings *h* and *i*, too, may be modified in form, providing they deliver the blast in a greater volume below than above.

I do not desire to claim broadly injecting jets of air on to the fuel or products of combustion in furnaces, as this has been heretofore done, but I claim as my invention, and desire to secure by Letters Patent—

1. A cupola or blast furnace, the interior of the lower portion of which is composed of the chamber *G*, with vertical walls, and above the latter the basin-like chamber *F*, contracted at the top, all substantially as specified.

2. The combination, with a cupola or blast furnace, of a system of tuyeres having openings so arranged as to discharge a blast of greater volume below than above, as set forth.

3. The air openings *w*, arranged in respect to the projection *m* and basin-like chamber *F*, as described. In testimony whereof I have signed my name to this specification in the presence of two subscribing witnesses:

JAS. DOUGHERTY.
